US00D867142S

(12) **United States Design Patent** (10) **Patent No.:** **US D867,142 S**
(45) **Date of Patent:** **** Nov. 19, 2019**

(54) **LIQUID CONTAINER**

(71) Applicant: **OMS INVESTMENTS, INC.**, Los Angeles, CA (US)

(72) Inventors: **Ryan Robert Berger**, Columbus, OH (US); **Richard Foster**, Powell, OH (US); **Timothy Michael Martin**, Westerville, OH (US); **Sara Ann Gordon**, Powell, OH (US); **George William Hill, III**, Powell, OH (US); **Jay F. Perkins**, Pickerington, OH (US)

(73) Assignee: **OMS Investments, Inc.**, Los Angeles, CA (US)

(**) Term: **15 Years**

(21) Appl. No.: **29/682,395**

(22) Filed: **Mar. 5, 2019**

Related U.S. Application Data

(60) Continuation of application No. 29/646,000, filed on May 1, 2018, now Pat. No. Des. 842,702, which is a division of application No. 29/579,366, filed on Sep. 29, 2016, now Pat. No. Des. 818,827, which is a continuation of application No. 29/537,264, filed on Aug. 24, 2015, now Pat. No. Des. 770,903, which is a continuation of application No. 29/449,014, filed on Mar. 14, 2013, now Pat. No. Des. 761,116.

(57) **CLAIM**

The ornamental design for a liquid container, as shown and described.

DESCRIPTION

FIG. 1 is a top, front, left side perspective view of an embodiment of a liquid container showing our new design; FIG. 2 is a front elevation view thereof; FIG. 3 is a rear elevation view thereof; FIG. 4 is a left side elevation view thereof; FIG. 5 is a right side elevation view thereof; FIG. 6 is a top plan view thereof; FIG. 7 is a bottom plan view thereof; FIG. 8 is a top, rear, right side perspective view thereof; and, FIG. 9 is a bottom, front, left side perspective view thereof. The evenly-dashed broken lines in the drawings illustrate the portions of the liquid container that form no part of the claim. The dot-dash broken lines in the drawings define the bounds of the claim and form no part thereof.

1 Claim, 9 Drawing Sheets
